Primary Examiner — Andrew Kerr*Assistant Examiner* — Courtney Clark-Rasheed(74) *Attorney, Agent, or Firm* — Reinhart Boerner Van Deuren s.c.(57) **CLAIM**

We claim the ornamental design for a thin metal cup, as shown and described.

DESCRIPTION

FIG. 1 is a front perspective view of a thin metal cup showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom plan view thereof.

The ornamental design which is claimed is shown in solid lines in the drawings.
